UNITED STATES PATENT OFFICE.

HERMANN POEHN, OF JERSEY CITY, NEW JERSEY, AND MAXIMILIAN JURUICK, OF NEW YORK, N. Y.

POCKET-AMMETER.

No. 839,637.

Specification of Letters Patent.

Patented Dec. 25, 1906.

Application filed December 1, 1905. Serial No. 289,749.

To all whom it may concern:

Be it known that we, HERMANN POEHN, a resident of Jersey City, in the county of Hudson and State of New Jersey, and MAXIMILIAN JURUICK, a resident of New York, in the county and State of New York, citizens of the United States, have jointly invented certain new and useful Improvements in Pocket-Ammeters, of which the following is a specification.

This invention has reference to improvements in pocket-ammeters, and pertains particularly to that kind of ampere-meters known as the "watchcase" type.

15 The novel ammeter is a direct-reading instrument. Its scale usually ranges from zero to thirty or forty or fifty amperes or any other suitable number.

It is the special object of this invention to 20 provide a pocket-ammeter with a peculiarly-shaped armature located between the poles of an electromagnet of nearly-circular form. The weight or the mass of the material of the armature is so arranged that the inner portion 25 of same is heaviest, while the ends are narrow and light.

The novel ammeter, further, is provided with a loose ring for the adjustment of the starting-point of the armature or its normal 30 position in relation to the poles of the electromagnet. This is not done, directly, but by means of the hair-spring generally employed in such instruments and by a pinion and gear-wheel, as will be fully explained farther down.

35 The invention is illustrated in the accompanying drawings, in which—

Figure 1 represents in top plan view a pocket-ammeter which embodies our invention. Fig. 2 illustrates same in top plan view with dial and pointer removed. Fig. 3 is a rear view of the instrument with the rear cover removed. Fig. 4 is a detail view of the essential operative mechanism, and Fig. 5 is a plan view of Fig. 4.

45 Similar characters of reference denote like parts in all the figures.

In the drawings, *a* represents the casing, which is cut out in the rear, as shown in Fig. 3. At the bottom an opening *b* is cut into

50 the casing to allow of passing through one end of the contact *c*. Just opposite this opening there is the knob *d*, which is hollowed out and provided with a screw-thread on the inside

for the purpose of receiving one end of the second contact *c'*.

Within the casing there is mounted a brass disk *e*, which has a central opening and a tongue *e'*. The tongue extends inwardly to the center of the disk. An electromagnet *f* of nearly-circular shape is secured on the disk 60 by means of screws. The core *f*² of the magnet consists of soft iron, which retains practically no residual magnetism when no current flows through same. The poles *f*¹ of the magnet are turned inwardly, as shown in Fig. 65 4. The magnet has two windings of wire. The two ends *w*₁*w*₂, one of each winding, are soldered to the metal disk *e*, while the two other ends *w'*₁*w'*₂ are soldered to a small piece of metal *g*, which is provided with a threaded opening 70 for receiving the one end of the contact *c* that has a thread on the outside. A ring of insulating material *c*² is secured to the contact *c*. Within the casing there is a curved piece of insulating material *c*³, which has a circular 75 opening for the passage of the contact *c*. The ring *c*² and the piece *c*³ insulate the contacts from the casing, which forms part of the circuit of the magnet-wire. The current passes from the contact *c* through the electromagnet, 80 the casing, the knob *d*, and out through the contact *c'*.

Upon the disk *e* there is mounted a bridge *h*. (See Fig. 2.) The bridge is secured in the center of the disk and extends upwardly 85 into a branch *h'*. It carries two small shafts *i*, *j*, which rest in the disk *e*, each on a hardened plate to insure of easy movement; but this is not shown on the drawings. The shaft *i* rests on the tongue *e'* of the disk *e* and passes 90 through the bridge *h* and dial *k*. A pointer *k'* is attached to the top end of this shaft. A small pinion *l* is mounted on the shaft *i* right below the bridge and a hair-spring *s* below the pinion. The shaft *j* carries a gear-wheel 95 *m* and below same the armature *n*, which is in one horizontal plane with the poles of the electromagnet. The bottom surface of the disk carries a loose ring *o*, which is surrounded by a supporting-ring *o'*. The ring *o* has a 100 rectangular arm *o*², extending upward. The outer end of the hair-spring is secured to this arm, while the inner end of same is fastened to a small hub on the shaft *i*.

The armature *n* also is made of soft iron, 105 which quickly demagnetizes. It is of pecul-

iar shape, resembling somewhat the letter **S**. As shown in Fig. 4, the armature is pointed at the two ends and increases in width toward the center cross-bar *n'*, which is broadest. In this way the weight of the armature is so distributed that the pointed ends, which are normally near the poles of the electromagnet, are very light, while the center cross-bar is relatively heavy. When 10 current flows through the electromagnet, then the distance between the heavy bar of the armature and the poles of the electromagnet decreases, because the armature is turned in accordance with the strength of the 15 current flowing through the instrument.

As above stated, the wire spring *s* has one end attached to the rectangular arm *o²* of the loose ring *o*, while the inner end is secured to the small hub on the pinion and spring shaft 20 *i*. By turning the loose ring the starting-point or the position of the armature ends in relation to the poles of the electromagnet may be adjusted. This is another feature of this invention. It is plainly understood that 25 the pointer *k'*, which is secured to the top end of the pinion and spring shaft, will move when the spring is affected by the armature, which moves the gear and pinion when current flows through the instrument.

30 Having thus described our invention, we claim as new and desire to secure by Letters Patent—

1. A pocket-ammeter comprising a casing, a metal disk mounted therein, an electromagnet secured to said disk, an **S**-shaped armature mounted on a movable shaft between the poles of the electromagnet, a gear-wheel on said shaft above the armature, a pinion mounted on a second shaft in the center of 35 the instrument, a hair-spring on the pinion-shaft, and a loose ring on the disk having an upward rectangular arm to which one end of 40

the hair-spring is secured whereby the position of the armature ends may be adjusted in relation to the poles of the electromagnet. 45

2. A pocket-ammeter comprising a casing of the watchcase type, a metal disk mounted therein, an electromagnet of nearly-circular form and having turned-in poles secured to said disk, an **S**-shaped armature mounted on 50 a movable shaft between the poles of the electromagnet, a gear-wheel on said shaft above the armature, a pinion mounted on a second shaft in the center of the instrument, a pointer on the top end of the pinion-shaft, 55 a dial below the pointer, a hair-spring on the pinion-shaft below the pinion, and a loose ring on the bottom surface of the disk having a rectangular arm to which one end of the hair-spring is secured whereby the position 60 of the armature ends may be adjusted in relation to the poles of the electromagnet.

3. In a pocket-ammeter an electromagnet of nearly-circular form and having turned-in poles, an **S**-shaped armature mounted between said poles and in one plane with same on a movable shaft, a gear-wheel on said shaft above the armature, a pinion mounted on a second shaft, a hair-spring on the pinion-shaft below said pinion, and a loose ring having a rectangular arm to which one end of the hair-spring is secured whereby the position 65 of the armature ends may be adjusted in relation to the poles of the electromagnet. 70

In testimony whereof we have hereunto 75 set our hands, this 29th day of November, 1905, in the presence of two subscribing witnesses.

HERMANN POEHN,
MAX. JURUICK.
